US00D965427S

(12) **United States Design Patent** (10) Patent No.: **US D965,427 S**
(45) Date of Patent: **** Oct. 4, 2022**

(54) **PACKAGING CONTAINER**

(71) Applicant: **Elopak AS**, Spikkestad (NO)
(72) Inventor: **Gerd Unni Kvam**, Hokksund (NO)
(**) Term: **15 Years**
(21) Appl. No.: **35/509,782**
(22) Filed: **Jan. 10, 2020**

(80) **Hague Agreement Data**

Int. Filing Date: **Jan. 10, 2020**
Int. Reg. No.: **DM/206837**
Int. Reg. Date: **Jan. 10, 2020**
Int. Reg. Pub. Date: **Jul. 10, 2020**
(51) LOC (13) Cl. **09-07**
(52) U.S. Cl. **D9/433**
